DESIGN FOR A DRESS ENSEMBLE

Edna Breer, New York, N. Y.

Application September 6, 1940, Serial No. 94,827

Term of patent 3½ years

To the Commissioner of Patents:

Be it known that I, Edna Breer, a citizen of the United States, residing at 102 West 79th St., New York city, in the county of New York and State of New York, have invented a new, original, and ornamental Design for a Dress Ensemble, of which the following is a specification, reference being had to the accompanying drawing, forming a part thereof.

Figure 1 is a front view of the dress ensemble showing my new design;

Figure 2 is a rear view thereof;

Fig. 3 is a front view of the dress section; and Figure 4 is a rear view thereof.

The pretzel-like figures appearing on the front and rear of the jacket of the dress ensemble constitute quilted-like trimming that is puffed out of the material from which the jacket is made.

I claim:

The ornamental design for a dress ensemble, substantially as shown and described.

EDNA BREER.
